TYPE-WRITING MACHINE.

No. 833,280.

Specification of Letters Patent.

Patented Oct. 16, 1906.

Application filed June 2, 1902. Serial No. 109,927.

To all whom it may concern:

Be it known that I, JESSE ALEXANDER, a citizen of the United States, residing at Brooklyn, in the county of Kings, State of New York, (whose post-office address is No. 541 Logan street,) have invented certain new and useful Improvements in Type-Writing Machines, of which the following is a full, clear, and exact description.

My invention relates to improvements in type-writing machines, and particularly to the ribbon movement in machines of the so-called "visible-writing" class.

The description herein will be more particularly confined to the mechanism for feeding, adjusting, and operating the ribbon movement as adapted to be used with a machine, as more fully set out in another application filed herewith.

The invention will be found to consist in the improvements hereinafter described, and shown in the accompanying drawings, in which:

Figure 1 is a plan view of mechanism embodying part of my invention. Fig. 2 is a vertical projection of the principal parts of the same. Fig. 3 is an enlarged plan view of details of the ribbon-spool and adjacent parts. Fig. 4 is a detail of the ribbon-spool shaft. Fig. 5 is a side elevation of a shift-key and bar with attached levers. Fig. 6 is a side elevation of another shift-key and bar with mechanism for raising and locking the ribbon-guide, and Fig. 7 is a detail of a locking device for the raising-shaft.

As shown in the drawings, A is a shaft, which may be termed the "universal" shaft, which is rocked whenever a type-bar strikes the universal bar B in the usual manner. C is a slotted lever connecting the universal bar B with this universal shaft A. In the slot of this lever C operates a pivot d at one end of a U-shaped lever D. The other end e of this lever connects with the bar E for elevating and operating at the proper time the ribbon-guides e' e'.

F is a stationary arm secured at a convenient point in the frame of the machine and which carries a pivot f. This pivot serves as 50 a guide for the ribbon-shifter G, which is itself pivoted at the lower end at g to one corner of the U-shaped lever D below the

pivot d. The outline of a frame of a machine is shown in dotted lines.

The mechanism so far described operates as follows: When the universal bar is moved backward by the striking against it of a type-bar in the usual manner, the lever C (more clearly appearing in Fig. 6) is rocked to the left. The ribbon-shifter G being at this time stationary, the pivot g is therefore stationary, and the pivot d of the U-shaped lever D is moved to the left, with the lever C working in the slot of the lever C. The other arm of the lever D, therefore, rises in what is substantially a straight line, carrying with it the ribbon-guides e' e'. This operation brings the ribbon up into the printing position before the face of the type which is about to strike upon the platen.

In machines of this general class it is preferred to use a double case of type, in which instance it is necessary that means should be provided for shifting from one case to the other. This I have done, as will appear more clearly in Figs. 5 and 6. H is a shift-key bar situated at the left-hand side of the machine and being pivoted at h. Integral with this bar or carried thereby is an arm h', which when the key is depressed moves to the left in Fig. 5, carrying with it the slotted bar J. Operating in the slot of this bar J is a pin j, carried by the lever k, which is pivoted on the rock-shaft K. In Fig. 6 is found the exact duplicate in the reverse of the parts so far described, in which H' is the shift-key bar and h' is the arm coöperating with the slotted rod J' and thus with the rock-shaft K by means of the lever k'. This rock-shaft K carries at a point near the central portion a second lever k'', which connects with a frame g'', carrying the wheel upon which the carriage runs. The carriage is therefore moved in order to bring into operation the case of type desired, as follows: The depression of either shift-key bar throws the sliding bar J or J' toward the front of the frame. The rear end of the slot therein engages with a pin carried by one of the levers k or k' of the rock-shaft K. This shaft is therefore rocked in such a manner as to throw the lever k'' upward, thus raising the carriage-supporting wheel or lifter. When the carriage is thus shifted from one case of type to the other,

it will be noted, particularly in Fig. 6, that the ribbon-shifter G, being attached to the frame g^2 , is lifted and in its upward movement slides upon the stationary pin f, which 5 operates in its slot and carries with it the U-shaped lever D, the pin d in the latter lever sliding in the slot of the lever C. When the carriage, therefore, is thrown onto the upper case of type, for instance, the U-shaped lever is carried bodily upward, together with the ribbon-guide e', and through substantially the same distance. The striking of the universal bar at this time by a type-bar throws the lever C to the left and 10 operates to raise the ribbon-guide, as before, through a distance sufficient to bring the ribbon under the printing position of the new case of type. At all other times than that in which the universal bar is operating 15 the ribbon is down below the printing position of the type. This feature insures that the writing shall be visible at all times except at the instant of printing. At t, in Fig. 5, I have shown a shaft which is connected by levers l' l² to the shift-key bar H. This shaft l carries the locking arm or plate L of Figs. 6 and 7. The pin j, which operates in the slot of J, may preferably project beyond the slot through to the other side of the 20 slide J in such a manner as to engage at the proper time with one of the notches l³ of the locking-arm L. When the shift-key bar H, therefore, is depressed, the shaft l is rocked and the locking-arm L is withdrawn from engagement with the pin j, thus leaving the 25 rocking arm k free to operate as soon as the end of the slot reaches the pin j. When, on the other hand, the shift-key bar H' is depressed and the rock-shaft K is operated, as 30 before described, the pin j slides from the position shown in Fig. 7, moving to the right into the outer notch l³ in the locking-arm L, where it is held in place, thus giving the machine a clear line of upper-case type. The 35 locking-arm L may be released by simply depressing the other shift-bar H, which drops the arm L. The key-arm H is therefore used when a single upper-case type is desired and the key-arm H' when several are 40 to be struck in the upper case. H acts afterward as a release-key. Any suitable means may be employed to hold the key-levers H and H' in their normal positions as is common with key-levers in type-writer 45 constructions.

The spools M, upon which the ribbon is wound, are loosely mounted upon the stub-shafts m and carry the ratchet-wheels m' m². These ratchet-wheels are operated, as will 50 hereinafter appear, by the movement of the pawls a' or a² in accordance with which one is in engagement therewith at the time. These spool-shafts m are made in such a manner as to be detachable from their supports in a ready and convenient manner—

for instance, as shown particularly in Fig. 4, in which the end of the shaft is recessed and slightly expansible or elastic, so as to be adapted to slip on over the bulb-shaped portion of a stationary support m³. For convenience in handling these shafts m the outer end may be provided with a button m⁴, forming in addition a bearing for the spring m⁵, which in its turn frictionally engages the bobbin-spool to furnish the desired tension 75 in the ribbon.

The ribbon N has at each end a pin n' and n² of sufficient length to operate in slots m⁶ and m⁷ in the frame of the ribbon-spools. The ribbon passes up around the roller-guides n³ n⁴, which are mounted on stationary shafts or rods in a plane parallel to the plane of rotation of the spools and at or near the central portion is guided by the movable rollers e and e', carried by the guide-rod E, as 80 before described. In the position shown in Fig. 2 the ribbon is raised and ready for the printing of a type.

The rod O (shown in Fig. 1) connects the two pawl-shifters o' and o², which are pivoted to the frame of the machine so that when one is moved to the right the other moves to the right. These pawl-shifting levers are slotted at p' p² to embrace the pawl-carrying arms A' A². The arms A' and A² are operated by the universal shaft. The outer ends p³ p⁴ of the pawl-shifting levers are adapted to rest in recesses of stationary catches Q' and Q², respectively, and thus be prevented from accidental lateral displacement. Stationary supports are provided at R' and R² for the double frame of levers S' S², which operate the pawl-shifting lever. The forked ends s³ s⁴ of these frame-levers engage with the ends p³ p⁴ of the ribbon-shifting levers o' and o² and at the upper end project into the path of the pins n' n², carried by the ends of the ribbon N.

The pawls a' and a² may be provided with cheek-pieces a³ and a⁴, which project around the sides of the ratchets and tend to keep the pawls in their proper operative position.

If now we consider the movement of the ribbon and the mechanism for shifting the same, we will find in Fig. 2 that in the particular position shown the ribbon has just been wound upon the right-hand spool and the pin n' at the left-hand end of the ribbon has just come into contact with the lever S' and thrown the left-hand shifting frame to the right, carrying with it, as will plainly appear, the pawl-shifting lever o' and at the same time the pawl-arm A', carrying the pawl a', and bringing this latter into an operative position relative to the ratchet m'. At 115 the same time by means of the connecting-rod O the right-hand pawl-shifting lever has thrown the right-hand pawl a² out of engagement with the ratchet m². Any operation, therefore, of the keys of the machine which 120

will move the universal bar and oscillate the universal shaft A' will draw down the pawl-arm A' and pawl a', thus turning the ratchet-wheel m' and ribbon-spool M' counter-clockwise through the space of one tooth. The release of the universal bar then releases the pawl a' in the reverse manner preparatory to another stroke. The operation continues in this manner step by step whenever the universal bar is operated until when the ribbon has been nearly all wound upon the left-hand spool and unwound from the right-hand spool. At this time pin n² at the right-hand end of the ribbon will be drawn to the outer end of the slot m' as the spool M' rotates to the left. As soon as this pin n² comes in contact with the upper end of the lever S² as it passes to the outer end of the slot m' the lever will be thrown to the left, taking with it the pawl-shifting arm o², and thus bringing the pawl a' into engagement with the ratchet m'. At the same time the connecting-rod O moves the left-hand pawl-shifting arm o' to the left and disengages the pawl a'. The operation is therefore reversed, and any further movement of the part of the universal bar will proceed to wind the ribbon upon the right-hand spool as the operation was before continued on the left-hand spool.

30 The general outline of a form of a machine which is convenient for embodying the invention as herein set forth is shown in dotted lines in the various figures and will more fully appear in the other application before referred to, the particular parts shown and described herein being confined particularly to the mechanism for lifting the ribbon and automatically reversing the direction of feed and for throwing the ribbon into the proper position in front of the type irrespective of whether the upper or lower case of type is in use. These improvements are obviously useful in connection with machines of other general construction, but are particularly adapted to use as described.

What I claim is—

1. In a type-writing machine, a ribbon-spool carrier comprising a stationary shaft having a bulb-shaped end, a shaft having a recess with yielding walls adapted to engage said bulb-shaped end, said second shaft carrying a coiled spring for frictionally engaging the ribbon-spool and having at the outer end an enlarged abutting piece, substantially as described.

2. In a ribbon-operating mechanism for a type-writing machine the combination of a pair of ribbon-spools having horizontal axes, a vertically-positioned and centrally-located ribbon-guide frame, mechanism for raising and lowering the same, and a stationary guide-rod on each side of said frame and parallel thereto.

3. In a type-writing machine, a universal rock-shaft, an arm extending forwardly

therefrom at each end, a pawl-arm pivoted to each of said forwardly-extending arms and standing in a substantially vertical position, a shifting-arm for each of said pawl-arms forming guideways therefor, a connecting bar between said shifting-arms, and a pair of ratchet-wheels having horizontal axes and adapted to be operated by the vertical movement of the pawl-arms.

4. In a type-writing machine, a universal rock-shaft, pawl-carrying arms operated thereby, with the ends formed into relatively stationary pawl-hooks, a pawl-shifting lever engaging each of said pawl-carrying arms, a rod connecting said shifting-levers, stationary catch-blades adapted to engage the ends of the said pawl-shifting levers and to hold them in the one or the other position, substantially as described.

5. In a type-writing machine, a universal rock-shaft, pawl-carrying arms operated thereby, pawls carried by said arms, a pawl-shifting lever engaging each of said pawl-carrying arms, a rod connecting said shifting-levers, stationary catch-blades adapted to engage the ends of the said pawl-shifting levers and to hold them in the one or the other position, and means for automatically moving said shifting-levers, substantially as described.

6. In a type-writing machine, a universal rock-shaft, pawl-carrying arms operated thereby, pawls carried by said arms, separate pawl-shifting levers engaging said pawl-carrying arms, a rod connecting said shifting-levers, stationary catch-blades adapted to engage the ends of the said pawl-shifting levers and to hold them in the one or the other position, and means for moving said shifting-levers comprising pivoted levers adapted to be automatically operated by the movement of the ribbon, substantially as described.

7. In a type-writing machine, a universal rock-shaft, pawl-carrying arms operated thereby, pawls carried by said arms, separate pawl-shifting levers engaging said pawl-carrying arms, a rod connecting said shifting-levers, stationary catch-blades adapted to engage the ends of the said pawl-shifting levers and to hold them in the one or the other position, and means for moving said shifting-levers comprising pivoted levers adapted to be automatically operated by pins carried by the ends of the ribbon, substantially as described.

8. In a type-writing machine, a universal rock-shaft, vertical pawl-carrying arms operated thereby, pawls carried by said arms, a pair of ribbon-spools rotatably mounted on horizontal axes, ratchet-wheels carried by said ribbon-spools adapted to be engaged by said pawls, horizontal pawl-shifting levers adapted to engage said pawl-carrying arms the frame of said ribbon-spools being slotted, pins carried by the ends of a ribbon adapted to slide

- in said slots, shifting-frames adapted to move said shifting-levers and to coöperate with the pins carried by the ends of said ribbon to automatically reverse the feed of the ribbon.
5. 9. In a type-writing machine, a movable ribbon-guide, a universal rock-shaft, a lever carried by said universal rock-shaft and a U-shaped lever pivoted at one corner and having a pin operating in a slot in the lever carried by said universal shaft, said U-shaped lever being connected with said ribbon-guide and adapted to raise the same, substantially as described.
10. In a type-writing machine, a universal lever operable by the key and type-bar mechanism and having a vertical slot, a vertically-movable ribbon-guide, and a pivoted lever connected to said guide and having a pin engaging in said slot, and means for lifting said guide independently of said universal lever.
11. In a type-writing machine, a universal bar, a slotted lever operated thereby, a ribbon-guide, a lever coacting with said slotted lever for operating said ribbon-guide, a stationary guide, a vertically-movable ribbon-shifter rod coacting with said stationary guide said ribbon-operating lever being pivoted to said ribbon-shifter rod so that said ribbon-guide may be operated by said universal bar when the ribbon-shifter rod is in either its upper or lower position.
12. In a type-writing machine, a universal bar, a slotted lever carried thereby, a ribbon-guide, a vertically-movable ribbon-shifter rod, a lever pivoted to said rod and connected to said guide and having a portion coacting with the slotted lever whereby the ribbon-guide may be operated by the universal bar when the ribbon-shifter rod is in either its upper or lower position, and means for locking said shifter-rod in its upper position.
13. In a type-writing machine, a universal bar, a slotted lever carried thereby, a ribbon-guide, a vertically-movable ribbon-shifter rod, a lever pivoted to said rod and connected to said guide and having a portion coacting with the slotted lever whereby the ribbon-guide may be operated by the universal bar when the ribbon-shifter rod is in either its upper or lower position, and means for locking said shifter-rod in its upper position.
14. In a type-writing machine, a universal bar, a slotted lever carried thereby a ribbon-guide, a vertically-movable ribbon-shifter rod, a lever pivoted to said rod and connected to said guide and having a portion coacting with the slotted lever whereby the ribbon-guide may be operated by the universal bar when the ribbon-shifter rod is in either its upper or lower position, and means for locking said shifter-rod in its upper position, comprising a notched lever and means for operating the same.
15. In a type-writing machine, a universal bar, a slotted lever carried thereby, a ribbon-guide, a vertically-movable ribbon-shifter rod, a lever pivoted to said rod and connected to said guide and having a portion coacting with the slotted lever whereby the ribbon-guide may be operated by the universal bar when the ribbon-shifter rod is in either its upper or lower position, and means for locking said shifter-rod in its upper position, comprising a notched lever and a shift-key for operating the same.
16. In a type-writing machine, a member having a vertical slot and operable by means of the key and type-bar mechanism, a vertically-movable ribbon-guide, a vertically-movable rod operable by means of the platen-shifting mechanism, and a lever pivoted to said rod and to said guide and having a pin operable in said slot.
17. A ribbon-feeding mechanism for a type-writing machine including, a pair of ribbon-spool-carrying shafts, ratchet-wheels therefor, a universal bar operable by means of the key and type-bar mechanism, a pair of flexible pawl members operable thereby for engagement with said ratchets, and a laterally-movable reversing device including arms engaging said pawl members.
